MULTIPLE CONTAINER

Clark V. Johnsten, Backus, Minn., assignor of
one-half to J. E. Hill and Nellie B. Hill, copart-
ners doing business as J. E. Hill and Company

Application December 11, 1944, Serial No. 567,679

1 Claim. (Cl. 206—56)

1

This invention relates to multiple or cellular containers adapted for containing and marketing measured quantities of liquids as well as solids and granular or pulverized material.

It is an object of my present invention to provide a simple and economical cellular container for housing with fluid-sealed effect and for commercially merchandising a number of measured quantities of solid, comminuted or liquid materials, thus offering a good commercial substitute for the cellophane sealed multiple packages frequently used in protecting and merchandising drugs as well as ampules used to contain and merchandise numerous liquid products.

A further object is the provision of a commercially practical cellular container comprising a plurality of adjacent pockets integrally constructed preferably by molding or die-forming operations and having independently removable fluid-tight closure elements associated therewith.

A more specific object is the provision of a multiple or cellular container of the class described, which lends itself particularly well to economical production and accurate filling by measuring and dispensing machines and which may be manufactured, filled and sealed very rapidly and at low cost.

Another object is the provision of a multiple container of the class described which lends itself well to be manufactured from rather fragile material, but which is reinforced by combination with a substantially rigid holder or frame which particularly lends itself to merchandising of the goods in the container cells.

These and other objects and advantages of my invention will be more apparent from the following description made in connection with the accompanying drawings, wherein like reference characters refer to the same parts throughout the several views and in which:

Fig. 1 is a back plan view of the complete container;

Fig. 2 is a cross section taken on the line 2—2 of Fig. 1;

Fig. 3 is a front plan view of the container holder showing its simulation to a natural produce from which the ingredients to be sold, are obtained; and

Fig. 4 is a side elevation of the container proper, detached.

In the form of my invention illustrated, the container proper is integrally constructed either by molding or die-forming suitable material such as plastic, composition or ductile metal to form a series of adjacent and preferably contiguous

cells or pockets 6, preferably but not necessarily of circular cross section and having closed inner ends 6a and open outer ends 6b, said outer ends of the several pockets 6 being integrally connected and aligned in a common plane and with the material forming said pockets preferably constituting a marginal out-turned flange surrounding the container body. This flange 7 is adapted to be utilized for attachment purposes and the material, when molded or processed, is preferably sufficiently resilient to permit flexing of opposite sides of the flange and the whole container body, to sufficient extent to permit of ready attachment to overlying attachment elements such as the pair of opposed lugs 8 utilized in the particular container holder illustrated in the accompanying drawings.

The container is of such structure as shown, that it may be held and rigidly supported on a suitable mat or jig for receiving material in each of the pockets from a suitable measuring and dispensing machine. Thereafter and successively the container may be moved and the individual pockets thereof all sealed and closed at the outer or rear ends thereof by the insertion of a plurality of small wads or plugs in the outer ends of the respective pockets. These wads or plugs 9 may be constructed of any suitable fluid-impermeable composition which is to some extent, compressible, to form a tight sealed joint between the peripheries of the plugs 9 and the inner peripheries of the pockets. A wad such as used in shot-gun shells, utilizing multi-layer materials or solid compressible materials having a very slight porosity, may be utilized and in the method of making my finished and filled package, multiple packing or wadding machines of a general nature used in filling shot-gun shells may be employed to apply the closure members 9 to the cellular pockets.

The container body may be constructed of rigid material and a label or advertising material applied over the outer end thereof, but I prefer to provide a holder shell or frame which particularly lends itself to merchandising and which further enables relatively light and ordinarily frangible material to be used for the cellular container proper. In this connection and for merchandising a number of prepared solid, granular and fluid materials, the holder shell may be moulded or otherwise constructed to resemble a natural object from which the specific goods or principal ingredients are obtained.

Thus in the form of the invention illustrated, the holder shell 10 is constructed such as by

3

moulding process, to accurately resemble the bulb of a garlic plant as being particularly appropriate to the use of my container for dehydrated, pulverized garlic, in concentrated form. The shell 10 is recessed at its rear to suitably accommodate the container body and is preferably rabbeted along the edge of the recess slightly to receive and countersink the marginal flange 7 of the container body. Suitable attachment means are provided as shown in the form of the two oppositely projecting attachment lugs 8 which may be integrally moulded or independently attached to the appropriate portions of the rear face of the holder shell 10. Container may be easily attached by flexing of the body and flanges to permit the edges of the flanges on opposite sides thereof, to be engaged by lugs 8.

In addition to disclosing a novel and commercially practicable multiple merchandising container, it will be seen that I have also disclosed a simple and commercially successful process for making and filling a multiple container which consists essentially in the steps of first forming a cellular container having independent adjacent pockets of general cup-shape with open outer ends, then successively moving the container body so formed, to a receiving position beneath a filling machine and simultaneously filling the several pockets so formed with measured quantities of material and thereafter, preferably simultaneously, applying closure plugs to the outer ends of the filled pockets of the multiple body to form fluid-tight closures for each and all of the said pockets.

From the foregoing description, it will be seen that I have provided a simple, inexpensive and attractive merchandising container of cellular type, well adapted to withstand shipping, handling and display and housing a number of measured quantities of both solid and liquid materials and rendering the materials in each of the pockets selectively available by ready removal of the appropriate closure plugs.

With my improved structure, pulverized or solid or liquid materials may be housed and protected from decomposition, corrosion or oxidation and the ingredients may be kept for long periods of time and the contents selectively utilized.

It will of course, be understood that the holder

shell 10 may be eliminated if the container proper 6 is constructed of substantially rigid material. It will further be understood that the container proper may be molded or otherwise constructed of rigid material with the integral cells 6 formed therein and that in such construction or molding the back of the container proper may be given any desired ornamental configuration and shape.

It will, of course, be understood that various changes may be made in the form, details, arrangement and proportions of the parts without departing from the scope of my invention.

What is claimed is:

15 A container of the class described, comprising
a solid frame having a recess in one side thereof
for accommodating a container body, a cellular,
molded, integrally formed container body con-
structed in the manner of a honeycomb with a
plurality of individual, cylindrical, cup-shaped
20 cells open at their outer ends, said body conform-
ing in shape to the recess of said frame, said in-
tegral body also including marginal, out-turned
flanges lying flush with the open outer ends of
said cells and adapted to overlie the recessed face
25 of said frame for attachment thereto and indi-
vidual closures for each of said pockets com-
prising slightly compressible cylindrical plug
members having fluid-tight connection with said
pockets and being individually removable there-
from without fracture.
